UNITED STATES PATENT OFFICE.

EDWARD D. LEWIS, OF SYOSSET, NEW YORK, ASSIGNEE TO THE CONTINUOUS RAIL JOINT COMPANY OF AMERICA, A CORPORATION OF NEW JERSEY.

INSULATED RAILWAY-RAIL JOINT.

SPECIFICATION forming part of Letters Patent No. 783,751, dated February 28, 1905.

Application filed June 1, 1904. Serial No. 210,649.

To all whom it may concern:

Be it known that I, EDWARD D. LEWIS, a citizen of the United States, residing at Syosset, in the county of Nassau and State of New York, have invented certain new and useful Improvements in Insulated Railway-Rail Joints; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

The objects of the invention are to reduce the cost of constructing insulated railway-joints, to secure greater strength and firmness at the joint in insulated joints of small cost, and to secure other advantages and results, some of which may be hereinafter referred to in connection with the description of the working parts.

The invention consists in the improved insulated railway-rail joint and in the arrangements and combinations of parts of the same, all substantially as will be hereinafter set forth, and finally embraced in the clauses of the claim.

Referring to the accompanying drawings, in which like figures of reference indicate corresponding parts in each of the several figures, Figure 1 is a front elevation of my improved joint when employing wood as the material of the insulating connecting-bars. Fig. 2 is a section of the same, taken at line *x* of Fig. 1. Fig. 3 is a section on line *y* of Fig. 4, showing the invention when the connecting-bars are constructed of a fibrous non-conductive composition pressed into shape; and Fig. 4 is a side elevation of the last said variety of construction.

In said drawings, 10 10 indicate the adjacent ends of two railway-rails, each having the head 11, the web 12, and base-flange 13 in any ordinary form. 14 14 indicate the connecting-bars at opposite sides of said rails. These are of insulating material adapted to obstruct or prevent the flow of electricity, either wood,

compressed paper, or other pulp, or combinations of insulating materials capable of withstanding the great pressure and impact to which rails and their connections are subjected. 15 indicates the bolts by means of which the connecting bars and rails are held in operative relation. The rail ends are electrically insulated from one another by interposed "posts" or plates 151, which are formed and operate in any usual manner to prevent the flow of the electrical current from one rail to the other.

Heretofore it has been common to force connecting bars or billets of wood between the head and base-flange of a rail, the wooden bar or billet serving both as an insulator of electricity and as a means of connecting two adjacent rails; but said insulating connecting-bars have never, so far as I am aware, served in addition as a support for the base-flange 13 of the rail. By my construction I not only simplify the joint as a whole, and thereby reduce the cost thereof, but with only a small addition of wood or insulating material I materially enhance the rail-supporting value of the insulation.

In the drawings the insulating connecting-bars are each shown to comprise a vertical upper portion 16, having oppositely-inclined bearings 17 and 18, adapted to engage the under side of the head of the rail and the upper side of the flange of the rail, respectively, laterally-extending lower portion 19, extending both laterally beyond the edge of the flange 13 and below the same sufficient to enable the desired strength to be secured. The laterally-extending lower portion is deeply grooved, as at 20, to receive the flange, the walls of the groove flaring in correspondence with sides of the flange to make a neat fit. The bottom portion 21 beneath the flange is integral with the upper part of the insulation and serves as a support for the bottom of the rail, thus adding greatly to the stiffness of the joint.

The parts thus described are ordinarily formed out of a single block or piece of wood, being subjected to a milling operation in any

suitable manner, and because of the simplicity of construction and cheapness of manufacture and the advantageous properties above recited the value and efficiency of the connection is materially enhanced.

As before stated, this construction while particularly suited for wooden joints may be of molded plastic insulating matter. When I employ paper or compressed material in the 10 construction of the joint, I prefer the construction shown in Figs. 3 and 4, in which case I may reduce the thickness of the body material 14 and employ metallic reinforcing-plates, of which 23 indicates a base-plate 15 adapted to be interposed beneath the insulating connecting-bars and side plates 25, rolled to conform to the shape of the outside of the connecting-bar and to protect the said connecting-bars from moisture, &c. These reinforcing-plates also serve the purpose of preventing abrasion of the insulating material under the heads of spikes and under the heads and nuts of the bolts.

Having thus described the invention, what 25 I claim as new is—

1. The improved insulating rail connection, comprising a bar or billet of insulating material having oppositely-inclined bearings adapted to engage the under side of the head of 30 the rail and the upper side of the base-flange thereof, and having a bottom portion adapted to extend underneath the base-flange and support the same, the inner side of said block or

billet having a flaring groove to receive the flange of said rail, substantially as set forth. 35

2. The combination with the rails, of connecting bars or billets of insulating material rigidly wedged between the head and flange of the rail at opposite sides thereof, the said bars being extended laterally and downwardly 40 beneath the flange of the rail, substantially as set forth.

3. The combination with the rails, of connecting bars or billets of electrically-insulating material rigidly wedged between the head 45 and flange of the rail and extending underneath said flange, reinforcing-plates disposed at the outside of said bars or billets of insulating material and bolts for holding said parts together, substantially as set forth. 50

4. The combination with the rails, of connecting bars or billets of insulating material rigidly wedged between the head and flange of the rail at opposite sides thereof, the said bars being extended laterally and downwardly 55 beneath the flange of the rail, and an insulating-post inserted between said rails, substantially as set forth.

In testimony that I claim the foregoing I have hereunto set my hand this 10th day of 60 May, 1904.

EDWARD D. LEWIS.
